[57] CLAIM

The ornamental design for a vehicle control simulator, as shown and described.

DESCRIPTION

FIG. 1 is a front perspective view of a vehicle control simulator showing my new design;

FIG. 2 is a rear perspective view thereof;

FIG. 3 is a right side elevational view thereof;

FIG. 4 is a bottom plan view thereof;

FIG. 5 is a left side elevational view thereof;

FIG. 6 is a front perspective view of a second embodiment of FIG. 1 showing my new design;

FIG. 7 is a rear perspective view thereof;

FIG. 8 is a left side elevational view thereof;

FIG. 9 is a bottom plan view thereof;

FIG. 10 is a right side elevational view thereof;

FIG. 11 is a front perspective view of a third embodiment of FIG. 1 showing my new design;

FIG. 12 is a rear perspective view thereof;

FIG. 13 is a left side elevational view thereof;

FIG. 14 is a bottom plan view thereof; and

FIG. 15 is a right side elevational view thereof.
